(57) **CLAIM**

I claim the ornamental design for a output connector, as shown and described.

DESCRIPTION

FIG. 1 is a perspective view of the output connector of the present invention;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.
